United States Patent

Des. 237,279
Patented Oct. 21, 1975

237,279

PRINTER OR SIMILAR ARTICLE

George R. Daniels, Oklahoma City, Okla., and John F. Graham, Sudbury, Mass., assignors to Honeywell Information Systems Inc., Waltham, Mass.

Filed Jan. 7, 1974, Ser. No. 431,515

Term of patent 14 years

Int. Cl. D14—02

U.S. Cl. D26—5 C

FIG. 2

FIG. 1 is a front perspective view of a printer showing our new design;

FIG. 2 is a front elevational view thereof;

FIG. 3 is a top plan view of the same.

The rear of the printer, not shown, is substantially plain and unornamented.

We claim:

The ornamental design for a printer or similar article, substantially as shown and described.
